UNITED STATES PATENT OFFICE

WALTER S. MAYER, OF PHILADELPHIA, PENNSYLVANIA.

ELECTRIC GROUND CLAMP.

Application filed February 24, 1922. Serial No. 538,898.

To all whom it may concern:

Be it known that I, WALTER S. MAYER, a citizen of the United States, residing in the city of Philadelphia, county of Philadelphia, and State of Pennsylvania, have invented certain Improvements in Electric Ground Clamps, of which the following is a specification.

This invention relates to clamps of the character applied to conduits for holding electrical conductors and connecting them with ground conductors.

The primary object of the invention is to provide an improved clamp of simple character that can be applied to conduits of different sizes and connected with ground wires readily, so as to make good electrical contacts with the conduit and the wire, without the use of solder.

20 The characteristic features of my improvements are disclosed in the following description and the accompanying drawings illustrating preferred forms embodying the same.

25 In the drawings, Fig. 1 is a perspective view of a device made in accordance with my invention; Fig. 2 is a side view of a section of the same having a bolt therein; Fig. 3 is a plan view of the device clamped on a conduit and to a conductor for grounding the same; Fig. 4 is a side view of a form of the construction connecting a conduit with a wire; Fig. 5 is a plan view of a modified form of the device connected with a wire 30 adapted to be bent around and clamped on a conduit, and Fig. 6 is a side elevation of the construction shown in Fig. 5.

The invention, in the form thereof illustrated in Figs. 1 and 2, comprises a 40 metal strip (preferably copper) having the straight section 1 containing the holes 2, the curved section 3 at the rear of the section 1, the flat section 4 extending rearwardly from the section 3, the curved or looped sections 5 connected with the section 4 and having the open space 6 between them, the section 7 extending forwardly from the parts 5 and having the curved terminal or seat 8 adjacent to the outer surface of the curve 3, and the lug 9 provided by metal cut from the space 6 and bent transversely to the section 4, the parts 4 and 7 having the holes 10 therein for the passage of a bolt 11.

55 As illustrated in Fig. 3, the section 1 is adapted to be bent around a conduit 12 from the section 3, which approximately fits

thereon, to approximate parallelism to the part 4, the appropriate hole 2 being brought into alignment with the holes 10. The bolt 11 is passed through a split spring washer 60 13 and through the aligned holes. A wire 14 has its end passed through the loops 5 and then bent back and passed through the loop 8 after the insertion of the bolt or this U-shaped end can be inserted between the parts 65 4 and 7 so that its parts 14' and 14'' will be in the respective seats 5 and 8 before the insertion of the bolt.

The tightening of the bolt 11 presses the part 1 against the part 9 which spaces the 70 parts 1 and 4, as the wire spaces the parts 4 and 7, so as to provide capacity in the separated parts to continue movement together under pressure, without contact, as a result of the action of the bolt together 75 with the washer thereon, which effects not only a close contact of the clamps with the conduit and with the wire initially, but maintains that contact, due to the resiliency 80 of the parts.

As illustrated in Fig. 4, the part 7 may be a substantial tangential extension from the loops 5 with the downwardly turned lip 8' at the forward end thereof, the depressed relation of this part 7 to the parts 5 and 8 85 (as illustrated in Figs. 1 and 2) being eliminated.

As illustrated in Figs. 5 and 6, the device comprises the section 1 with the holes 2 90 therein, the curved section 3 at the rear end thereof, the section 4 at the rear of the section 3 with the lugs 4' cut in and turned outwardly from the sides thereof, and the downwardly bent lug 9' formed at the rear end thereof. In this construction, the 95 ground wire 14 has the U formed by its end sections 14' and 14'' disposed between the lugs 4' so as to be tightly engaged by the washer 13 when drawn down by the bolt 11 passing therethrough, through the section 4 100 and the section 1 when bent around a conduit into contact with the lug 9'.

It will be understood that, as in the previous construction, this form of the device is adapted to be applied to the conduit 12 105 by placing the concave section 3 thereon and bending the section 1 around the conduit until the appropriate hole 2 is in approximate registration with the hole through the section 4. The bolt 11 is passed through the registering holes and drawn up to clamp the part 1 against the part 9' and the parts 14'

and 14" against the part 4, the open space between the parts 1 and 4 and the split washer 13 permitting the clamp to be drawn up tightly on the conduit, the ground wire 6 engaged tightly to the clamp, and the close contacts maintained as a result of the constant tension.

Having described my invention, I claim:

1. An electric clamp comprising an integral strip of material having a section adapted for engaging a conduit, a section adapted for engaging a conductor, a lug for spacing said sections apart and means comprising a bolt passing through both of said sections for drawing said section first named against said lug and said conductor against said section second named.

2. An electric clamp comprising a section adapted to be clamped around a conduit, a section adapted to be clamped to a conductor, a lug fixed to said section second named for spacing said section first named relatively thereto, and means comprising a bolt adapted to pass through said sections for pressing said first section against said lug, clamping said first section on said conduit and clamping a conductor to said section second named.

3. An electric clamp comprising a perforated flexible section adapted to be engaged on a conduit, a perforated part integrally connected therewith and having a lug projecting therefrom, loops having a space between them integrally connected with said part on opposite sides of said lug and a perforated part integrally connected with said loops, in combination with a bolt adapted to pass through said parts to clamp them upon a wire and through said section 40 to clamp it on a conduit.

4. An electric clamp comprising a strip of flexible metal having a perforated section adapted to be bent around a conduit, a perforated section having a lug thereon for engaging said section first named, a loop at the rear of said section second named on the opposite side thereof from said lug, and

means for drawing said section first named against a conduit and for drawing said loop against a wire.

5. An electric clamp comprising a sheet of material forming a wire engaging section provided with a lug bent therefrom and wire engaging means bent therefrom oppositely to said lug and a conduit engaging section consisting of an apertured strap, and means for drawing said strap against said lug and a wire against said wire engaging section.

6. An electric clamp comprising a conduit-engaging strap and a conductor-engaging socket consisting of an extension of said strap and a clip hingedly connected therewith, said socket containing aligned bolt apertures and having conductor-engaging walls on opposite sides of the axis thereof to receive the looped end of a conductor, said strap containing an aperture adapted for registration with a bolt passed through said socket apertures between said walls for 70 engaging together said looped conductor and said socket members, the legs of the conductor loop being drawn against the same surface of the extension and said apertured strap section being drawn by said bolt toward the face of said extension opposite said conductor-engaging walls.

7. An electric clamp comprising a flexible conduit-engaging strap, a clip forming with said strap a plurality of channels for seating a looped wire, and a bolt passing through said clip between said channels to clamp both legs of the looped wire against the same surface of said strap; said strap having an apertured section through which said bolt passes and by which said section is drawn toward a strap section adjacent to said clip, the channel-forming section of the strap lying between and substantially parallel with the clip and apertured strap-section.

In testimony whereof I have hereunto set my name this 23rd day of February, 1922.

WALTER S. MAYER.
